COMBINED NAIL POLISH BOTTLE AND FINGER REST

Robert Henry and Harry Poris, New York, N. Y.

Application April 24, 1956, Serial No. 41,191

Term of patent 14 years

(Cl. D86—10)

FIG. 2.

FIG. 1.

FIG. 3.

FIG. 4.

FIG. 5.

Fig. 1 is a side elevational view of a combined nail polish bottle and finger rest, showing our new design.

Fig. 2 is a top plan view thereof.

Fig. 3 is a front elevational view as seen from the left of Fig. 1.

Fig. 4 is a longitudinal sectional view thereof.

Fig. 5 is a cross-sectional view on line 5—5 of Fig. 1.

The dotted line showing in the drawing is for illustrative purposes only.

We claim:

The ornamental design for a combined nail polish bottle and finger rest, substantially as shown and described.
